UNITED STATES PATENT OFFICE.

HENRY E. MARCHAND, OF ALLEGHENY, PENNSYLVANIA.

MEASURING-PUMP.

SPECIFICATION forming part of Letters Patent No. 327,890, dated October 6, 1885.

Application filed November 13, 1884. Serial No. 147,918. (No model.)

To all whom it may concern:

Be it known that I, HENRY E. MARCHAND, a citizen of the United States, residing at Allegheny city, in the county of Allegheny 5 and State of Pennsylvania, have invented new and useful Improvements in Measuring-Pumps, of which the following is a specification.

My invention relates to measuring-pumps 10 of the class employed for drawing oil from the tanks in which it is contained, and the purpose thereof is to simplify the construction, reduce the cost of manufacture, improve the operation of this class of apparatus, and to 15 provide a single-acting pump which will throw a continuous stream of oil.

My invention consists of the several novel features of construction and combinations of parts, hereinafter fully described, and definitely 20 pointed out in the claims annexed to this specification.

Referring to the drawings forming part of this application, Figure 1 is a vertical section taken centrally through the pump-cylinder and adjoining parts. Fig. 2 is a horizontal section taken in the plane $\alpha\alpha$, Fig. 1. Fig. 3 is a horizontal section of the piston-coupling detached. Fig. 4 is a central longitudinal section of a portion of the outlet-pipe 25 with its contained check-valve.

In the said drawings, the reference-numeral 1 denotes the pump-cylinder, which is constructed with an open top surrounded by a collar or flange, 2, to which is securely bolted 30 a dome-shaped cover, 3, which forms a liquid-chamber having a central opening, 4, to which the goose-neck or outlet 5 is applied.

Within the cylinder 1 is placed a piston, 6, having an elastic packing-ring, 7, contained 35 within a chamber cut upon the periphery of the piston-head, and provided with an annular flange, 8, rising from its upper side. Upon this flange is secured a coupling intermediate between the piston and the piston-rod 9. This 45 coupling is composed of a ring, 10, resting upon the flange 8, and having a flange, 11, which fits within said flange.

Radial arms are cast integral with the ring 10, forming a spider, 12, whereupon are mounted 50 ears or lugs 13, between which the end of the actuating-rod 9 is pivoted. The other end of

said rod is perforated to receive a wrist-pin, 14, formed upon a crank-arm, 15, which is carried by a crank-spindle, 16, the latter being journaled in an arbor, 17, the axis of the 55 spindle and that of the arbor being parallel, but not coincident, the construction being substantially the same as that shown in Letters Patent No. 287,697, granted to me the 30th day of October, 1883.

6c

The arbor 17 has bearing in a box, 18, formed upon one side of the dome 3, and provided with a detachable cap, 19, which forms, in connection with the outer end of said box, a stuffing chamber containing packing 19^a. A 65 collar, 20, is formed upon the arbor 17 to limit its inward movement, and the packing or stuffing lies against said collar and holds it closely in place. In the outer end of the spindle 16 is formed a channel or groove, 21, 7c which receives the end of a set-screw, 22, passing through a threaded aperture in the arbor 17, and through the sleeve 23 upon the end of the crank 24. This construction prevents the set-screw from burring the spindle 75 when it is set up against it.

The lower solid end of the cylinder is turned off to form a neck, 25, which enters a collar, 26, surrounding an opening in a plate, 27, upon which the piston is mounted and secured 8c by a set-screw, 28, passing through a boss upon said collar. The plate 27 is provided with legs 29, of any suitable form, and forms a stand for the pump, a flange, 30, being cast or otherwise formed upon the periphery of the plate 85 to catch the drip or leakage from above.

In the lower end of the cylinder 1 is formed a central opening, 31, which receives the outlet-pipe 32. This opening communicates with a central aperture in the piston 6, within which 9c is seated a puppet-valve, 33, projecting below the piston and into an enlargement of the opening 31. This valve has a stem, 34, which moves in an aperture, 35, formed at the juncture of the radial arms 12, and by which the 95 valve is guided.

The eduction-pipe 32 is provided below the cylinder with a check-valve composed of two separate disks, 36 and 37, mounted upon a stem, 38, and seating upon annular flanges 100 36^a and 37^a, formed upon the interior of the pipe. The upper valve-disk, 36, is the larger,

the lower one being of such size that it will pass through the seat 36^a to permit the removal of the valve. Wire screens 39 are placed above and below the valve, and the ends of 5 the valve-stem pass through said screens and guide the valve in its movement, causing it to seat accurately.

The top or stand plate, 27, which is preferably made of circular form, has an extension, 27^a, upon which is mounted a drip-cup, 40, having an inlet or drip-receiving pipe, 41, which leads back to the tank. The drip-cup is fastened in place by a set-screw, 42, and may be provided with a screen to prevent the passage 15 of foreign substances into the tank beneath. The socket or opening which receives the drip-cup may also be provided with apertures 43, through which the oil leaking from the packings and retained by the flange 30 may 20 enter the inlet-pipe 41 and return to the tank.

The construction shown may be varied considerably without departing from my invention. For example, the crank-spindle may, instead of having a groove, 21, be turned 25 down; or diminished or, on the other hand, the chamber in the arbor in which the spindle has bearing may be enlarged at the point where the set-screw engages, the crank-spindle remaining of equal diameter throughout. In 30 either case the same result—viz., preventing the crank-spindle from being obstructed in rotary adjustment by the metal burring up against the arbor under the set-screw—is accomplished.

35 This pump, though a single-acting pump, will throw a steady and continuous stream, produced by the accumulation in the reservoir 3, in excess of the discharge through the outlet 5.

40 By locating the check-valve in the pipe leading to the pump-cylinder I am able to use a single valve only in the pump; and, moreover, the check-valve, being at some little distance from the piston and cylinder, the oil

above the check-valve makes an elastic cushion 45 for the piston, which materially promotes the operation.

I do not here claim the construction of table or stand for supporting a pump cylinder or case and a drip-cup; nor do I 50 claim the peculiar manner of constructing and supporting a pump cylinder or case on the table; nor do I claim a pump-cylinder having an air and fluid reservoir with an outlet leading therefrom, combined with a drip-cup communicating with a pipe to return oil-drippings back to an oil-tank. Such features are embodied and claimed in a separate application for Letters Patent filed by me March 10, 1885, Serial No. 158,380. 60

What I claim is—

1. In a single-acting measuring-pump, the combination, with the cylinder having an air-reservoir, of a valve piston, an eduction-pipe having annular valve-seats and communicating 65 with said cylinder, and a double check-valve in said pipe consisting of a large and a small valve-disk mounted upon the same valve-stem, the ends of the stem passing through and being guided by wire screens in the pipe, 70 substantially as described.

2. In a measuring-pump, the combination, with the outlet-pipe leading to the pump-cylinder, of a check-valve composed of two imperforate disks, the upper a large and the 75 lower a small one, both mounted upon the same stem and engaging with the upper surfaces of annular valve-seats projecting from the inner surface of the pipe, said valves being lifted from their seats by the lifting of the 80 fluid through the outlet-pipe, substantially as described.

In testimony whereof I affix my signature in presence of two witnesses.

HENRY E. MARCHAND.
